S. GASPARAITIS

FOUNTAIN PAINTBRUSH

Filed Dec. 10, 1921

FIG. 1.

FIG. 3.

FIG. 2.

INVENTOR

Stanley Gasparaitis

Charles W. Niles
Atty.

bv

UNITED STATES PATENT OFFICE.

STANLEY GASPARAITIS, OF CHICAGO, ILLINOIS.

FOUNTAIN PAINTBRUSH.

Application filed December 10, 1921. Serial No. 521,289.

To all whom it may concern:

Be it known that I, STANLEY GASPARAITIS, a citizen of the United States, and a resident of the city of Chicago, in the county of 5 Cook and State of Illinois, have invented certain new and useful Improvements in a Fountain Paintbrush; and I do hereby declare that the following is a full, clear, and exact description of the same, reference being had to the accompanying drawings, and to the numerals of reference marked thereon, which form a part of this specification.

This invention relates to fountain paint brushes in which paint is delivered to the 15 brush through its handle from a suitable container by means of air or other pressure.

It is an object of this invention to provide a new and improved brush.

It is a further object of this invention to 20 provide a brush and a setting for its bristles that may be manufactured and sold as a unit apart from the handle.

It is a further object of this invention to 25 provide a removable substitute for the sheet metal ferrule usually found on paint brushes.

Other and further important objects of this invention will be apparent from the disclosures in the accompanying drawings and specification.

30 The invention (in a preferred form) is illustrated in the drawings and hereinafter more fully described.

On the drawings:

Figure 1 is a side elevation of a brush constructed in accordance with the present invention.

Figure 2 is a transverse section of the brush.

Figure 3 is a longitudinal section of the 40 brush.

As shown on the drawings:

The brush is formed with a hollow handle 1 extended to accommodate the usual wide flat form of paint brush although it may 45 be given any other shape to accommodate any desired form of brush.

The edge of the handle nearest the brush extends beyond the setting of the bristles and forms a housing therefor, as shown at 50 2. A web extends across the hollow handle at the beginning of this housing to afford a bearing against which the setting of the bristles abuts, as shown at 3. It includes several portions which extend completely 55 across the narrow part of the brush, as shown at 4. At each end of the housing ears 5

are provided for the reception of screw 6 for attaching the brush.

The setting of the bristles comprises a metal frame 7, which is provided with a flange 8 adapted to seat upon the edge of the housing. This flange also has ears 9 extending over the ears 5 to cooperate with the screws or bolts 6. The central portion of the housing is occupied by a filler block 10. Through this filler block go holes 11, preferably each lined with a metal sleeve, although the latter is not essential. The filler block 10 is surrounded by a piece of cloth 12 which extends up into the midst of the brush. The space around the filler block, both within and without the cloth 12 is filled with bristles. Also there are bristles abutting against the upper surface of the filler block and completely filling the space within the cloth. The bristles are all held in place by glue which makes the block and the ends of the bristles and of the cloth constitute one solid mass filling the frame 7 completely. At a distance from the housing the bristles are surrounded by a frame 13. This frame is supported from the ears 9, being held in place by the bolts or nuts 6. For this purpose the frame is provided with upright parts 14 and with horizontal ears 15.

In the operation of the device the brush is connected to the source of paint under pressure which enters the handle 1 and passes through the holes 11 and emerges in the midst of the bristles inside of the cloth 12.

The action of the bristles in spreading of paint tends to produce too great an accumulation of paint at each edge of the brush. This is partly prevented by the action of the cloth and partly by the frame 13 in restraining the degree to which the bristles flex. A uniform distribution of paint throughout the width of the brush is thus obtained.

The brush may be cleaned by blowing air under pressure through the handle 1.

In applying the brush to the work the frame 13 acts to prevent too great a flexure of the bristles in the same way that the usual sheet metal ferrule surrounding the brushes now employed acts. The collection of bristles with the parts that are permanently attached thereto, namely the frame 7 and the filler block 10 are firmly fastened together by means of a filling of glue, rubber or other cementing material. In addition,

if desired, screws may be passed through the walls of the frame 7 into the filler block. The brush apart from the handle and the paint supplying arrangement may be sold as 5 a separate unit, to replace brushes which have been worn out or so that the painter may have a supply of brushes at hand which would enable him to change quickly from one color to another by merely blowing out 10 the paint from the tube and fixtures and substituting a new can of paint and a fresh brush.

I am aware that numerous details of construction may be varied through a wide 15 range without departing from the principles of this invention, and I therefore do not purpose limiting the patent granted otherwise than necessitated by the prior art.

I claim as my invention:

- 20 1. A paint brush comprising a hollow handle, bristles supported by said handle, a pervious cloth funnel arranged within the bristles for controlling the flow of paint to the bristles from said handle and a rigid 25 frame secured to said handle and surrounding said bristles at a distance from the point of attachment of said bristles adapted to retain the latter in contact with said funnel.
2. A paint brush comprising a hollow handle having a recess in its end, a filler block

seated in said recess, means securing said block to the handle, an annular ring of bristles arranged around the periphery of said block, a cloth funnel arranged around the last named set of bristles, and a second set 35 of bristles arranged around the funnel, said filler block having an aperture therein for the passage of paint from said handle to said funnel, and a frame secured to the handle and surrounding said bristles at a distance from said filler block to retain said outer set of bristles in contact with said funnel.

3. A paint brush comprising a hollow handle, a filler block attached to said handle, an annular ring of bristles arranged around the periphery of said block, a funnel arranged around the last named set of bristles, and a second set of bristles arranged around the funnel, said filler block having 40 an aperture therein for the passage of paint from said handle to said funnel.

In testimony whereof I have hereunto subscribed my name in the presence of two subscribing witnesses.

STANLEY GASPARAITIS.
